UNITED STATES PATENT OFFICE.

JOSHUA J. NIX, OF ROYERSFORD, PENNSYLVANIA.

GAS OR OIL HEATER.

SPECIFICATION forming part of Letters Patent No. 615,193, dated November 29, 1898.

Application filed May 27, 1898. Serial No. 681,936. (No model.)

To all whom it may concern:

Be it known that I, JOSHUA J. NIX, a citizen of the United States, residing at Royersford, in the county of Montgomery and State 5 of Pennsylvania, have invented new and useful Improvements in Gas or Oil Heaters, of which the following is a specification.

My invention relates to gas or oil heaters; and its object is to provide an improved construction of the same by which a room or other place may be effectually and thoroughly heated in an economical manner.

The invention consists in the novel construction and combination of parts herein- 15 after fully described and claimed.

In the accompanying drawings, Figure 1 is a front view of a heater constructed in accordance with my invention. Fig. 2 is a trans- 20 verse sectional view of the same. Fig. 3 is a horizontal section on the line $x x$, Fig. 1.

In the said drawings the reference-numeral 1 designates the base of the heater, consisting of the hollow sides 2, the hollow back 3, and a number of forwardly-projecting cham- 25 bers 2^a, similar to sides 2, forming a water- back for containing water. The said back is curved, as shown, and is enameled or coppered on its surface, so as to form a reflector. The upper end of said back is extended for- 30 wardly and curved downwardly, forming a water-chamber 4, which is a part of the water- chambers formed by the hollow sides, back, and intermediate chambers 2^a. In rear of said base is a steam-chamber 5, formed by the ver- 35 tical walls 6, and the upper end is turned out- wardly at a right angle, forming a hollow man- tel or shelf 7.

The numeral 8 designates a series of pipes connecting the upper end of the water-back 40 with the steam-chamber.

Located in front of the upper end of the water-back is a vapor pan or trough 9 for containing water. A passage 10 is thus formed between the said pan or trough and the front 45 of the water-chamber 4 for the escape of the heat and products of combustion from the burners. This pan at each end is connected with the water-back by means of nipples 12.

The numeral 13 designates a series of Wels- 50 bach burners, connected with a gas-supply

pipe 14 by means of branch pipes 15, provided with stop-cocks 16. By employing such burners as the heating means the room will also be lighted; but where gas is not available these burners may be removed and any suitable liquid-hydrocarbon burners may be substituted therefor. 55

The nipples which connect the vapor-pan and water-back are located below the water-line, and the water is supplied to the water- 60 back from the pan through such nipples, and the pan being open the height of the water can always be readily ascertained, so that it can be replenished when too low.

In using the device the water-back is filled 65 with water to the proper level, as seen in Fig. 2, and the burners are lighted, heating the water contained in the water-back and converting it into steam, which will enter the steam-chamber and heat the extension and 70 mantel. The heat will also be reflected from the curved water-back into the room and the products of combustion will escape through the passage between the vapor-pan and wa- 75 ter-back up in front of the extension and will be deflected into the room. In front of the 75 said water-back is a glass plate 17, the front of which is provided with convex portions 18 and the rear or inner sides made plain or flat, thus forming what is known as an ordinary 80 "bull's-eye." An apron of asbestos may be placed in front of this bull's-eye if it is desired to prevent the light from shining through.

By my invention I provide a hot-air and steam heater which will heat a room thor- 85oughly and uniformly, and the vapor from the vapor-pan will impart the requisite hu- midity to the atmosphere of the room.

Having thus fully described my invention, what I claim is— 90

In a heater of the character described, the combination with the water-back comprising the hollow sides and back, the forwardly-ex- 95 tending intermediate portions forming a se- ries of separated chambers and the forwardly- extending upper end curved at the lower side and the heaters located in said intermediate chambers, of the vertical walls forming a steam-chamber and the hollow mantel at the upper end, the pipes connecting said water- 100

back and steam-chamber, the vapor-pan located in front of the forwardly-extending upper end of the water-back forming an air-passage therebetween and the nipples connecting said pan with the water-back, substantially as specified.

5 In testimony whereof I have hereunto set

my hand in presence of two subscribing witnesses.

JOSIIUA J. NIX.
